Primary Examiner — Brett Miller*Assistant Examiner* — Sara Michie Pottenger(74) *Attorney, Agent, or Firm* — Patterson + Sheridan, LLP(57) **CLAIM**

The ornamental design for a cattle guard as shown and described.

DESCRIPTION

FIG. 1 is a top, front, left side perspective view of a cattle guard showing my new design according to a first embodiment.

FIG. 2 is a top plan view thereof.

FIG. 3 is a bottom plan view thereof.

FIG. 4 is a front elevational view thereof, the rear elevational view being a mirror image.

FIG. 5 is a left side elevational view thereof, the right side elevational view being a mirror image.

FIG. 6 is a top, front, left side perspective view of the cattle guard according to a second embodiment; and,

FIG. 7 is a top, front, left side perspective view of the cattle guard according to a third embodiment.

The front elevational view, the rear elevational view, the left side elevational view, and the right side elevational view of the second and third embodiments are the same as the views illustrated and described with respect to FIGS. 4 and 5.
